UNITED STATES PATENT OFFICE

FORREST A. WALKER, OF SYRACUSE, NEW YORK, ASSIGNOR TO WALKER DISHWASHER CORPORATION, OF SYRACUSE, NEW YORK, A CORPORATION OF NEW YORK

IMPELLER FOR MECHANICAL DISHWASHERS

Application filed November 23, 1926. Serial No. 150,230.

This invention relates to a mechanical dish-washer of the class set forth in my pending application Serial No. 122,277, filed July 14, 1926, and refers more particularly to the construction of the impeller.

In machines of this type the dishes and other utensils to be washed are supported in suitable open-work trays or baskets within a cylindrical vat having a conical bottom in which a limited quantity of washing fluid is placed to be impelled or circulated upwardly and circumferentially by the rotary impeller which is placed within and in close proximity to the conical bottom in a plane below the dish-supporting trays and driven by a vertical shaft extending through a gland in the apex of said bottom.

Under these conditions it is highly important that the washing fluid be impelled upwardly with considerable force and in such manner as to effect a glancing contact with all of the dishes or other utensils throughout the area of the superposed trays or tray and the main object of the present invention is to accomplish this result in the most efficient and expeditious manner with a minimum consumption of power by reducing the resistance to rotation of the impeller by the inertia of the fluid and also by utilizing the centrifugal motion of the fluid against a continuous baffle connecting the outer edges of the impeller blades in spaced relation to the hub of the impeller.

In other words one of the objects is to construct the impeller blades in such manner that they will pick up and deflect the fluid upwardly and circumferentially with a minimum resistance and power.

Another object is to gradually incline the lower ends of the blades below the baffle band more nearly toward a horizontal plane and in such manner as to gradually lift the fluid and deflect it against the baffle band during the initial pick-up of the water by the blades and to utilize the baffle band as the means for force of upward deflection of the fluid and baffle resistance of the band for effecting the continued upward movement of the fluid with a minimum consumption of power.

Other objects and uses relating to specific

parts of the device will be brought out in the following description.

In the drawings:

Figure 1 is a top plan of the detached impeller with the baffle band thereon.

Figure 2 is a side view of the impeller showing the baffle ring partly broken away and one of the blades partly in section.

Figure 3 is a vertical sectional view taken on line 3—3, Figure 1.

Figure 4 is a sectional view on a reduced scale of the impeller and adjacent portions of the vat in which it is located together with a portion of the driving shaft for the impeller.

As shown in Figure 4 the top or vat is provided with the usual conical bottom —1— having an opening in its apex in which is secured the lower end of a post —2— to form a water-tight gland therewith, the upper end of the post extending some distance above the apex of the bottom —1— for receiving and supporting a rotary vertical shaft —3— having its upper end extending beyond the top of the post —2— and —3— for receiving the impeller as —4—.

The impeller —4— comprises an upright hollow tubular hub —5— having a plurality of, in this instance two, diametrically opposite and laterally projecting blades —6—, the outer edges of which are connected by a continuous circumferentially-extending annular band or baffle ring —7— which together with the blades —6— and hub —5— are preferably cast of aluminum or other suitable material to form a single unit but obviously may otherwise be assembled if desired.

The length of the hub —5— is slightly greater than the length of the portion of the post —2— extending into the vat —1— while the interior diameter thereof is slightly greater than the diameter of said post, said hub with the impeller blades —6— and baffle ring —7— thereon being placed over and upon the upper end of the post —2— and has its upper end provided with a reduced threaded opening —8— which is screwed upon the upper threaded end of the shaft —3— preferably in a direction opposite to the direction of rotation of the impeller so

as to cause the latter to tighten when in operation and also permitting easy and quick removal of the impeller from the shaft when at rest.

It is now clear that the impeller is supported entirely upon its upper end upon and is driven by the shaft with its remaining portions or skirt encircling the post —2— with just sufficient clearance between the hub —5— and post to avoid friction one with the other, it being understood that the shaft —3— is journaled within the post in such manner as to hold the impeller co-axial therewith.

15 The impeller —4— is rotatably supported within the apex of the bottom of the vat and, therefore, within the greatest depth of the washing fluid therein, which fluid is normally maintained at a pre-determined level at or 20 near the level of the top of the impeller blades, the lower ends of said blades being actively disposed in proximity to the bottom —1— with just sufficient clearance to avoid contact therewith.

25 The diameter of the impeller is considerably less than that of the cylindrical side walls of the vat and is regulated somewhat by the inclination of the bottom —1— and by the normal depth of the washing fluid 30 therein so that the lower edge of the baffle ring —7— will lie in close proximity to the adjacent portion of the bottom with just sufficient clearance to avoid contact therewith while its upper edge will be at or near the 35 level of the washing fluid.

The upper edges of the blades —6— and baffle ring —7— are preferably disposed in the same horizontal plane while the vertical depth of the blades is considerably greater 40 than that of the baffle ring due partly to the conical formation of the bottom —1— of the vat, the baffle ring being preferably cylindrical and concentric with the axis of the impeller.

45 It will be noted, however, that the vertical depth of the ring is proportioned somewhat to the amount of projection and forward inclination of the lower portions of the blades below the ring.

50 Each blade —6— and particularly the front face thereof is curved downwardly and forwardly from its upper edge to its lower edge with gradually diminishing radii in the direction of rotation to form substantially 55 one-half of a parabola, the inclination of the lower portions of the blades being gradually but more abruptly increased to a horizontal as it approaches the lower free edge of the blade as shown more clearly in Figure 2, the 60 object of which is to permit the lower free edge of the blade to enter the fluid with a minimum resistance by the inertia of said fluid and then to gradually lift or deflect the fluid upwardly and rearwardly against the 65 front face of the blade which continues the

gradual upward deflection of the water aided by the momentum of the latter as it is picked up by the approximately horizontal lower free edge of the blade.

It will be noted upon reference to Figure 70 2 that the angles of the portions of the blades between the lower and upper ends of the baffle ring —7— are more nearly vertical than the lower ends of the blades which are more nearly horizontal and it is found that for the 75 speed with which this impeller is rotated the best results are obtained by making the portion of the blade between the upper and lower ends of the baffle ring at an angle of approximately 80 30 degrees to the axis of the impeller, this angle gradually increasing toward a horizontal at the lower front edge of the baffle thus producing a curved impact face which is found to be the most efficient in lifting and distributing the water against the 85 dishes with a minimum power.

It will also be noted upon reference to Figure 1 that the inner portions of the blades and particularly the front faces thereof are 90 substantially tangential to the corresponding sides of the hub while the outer portions are gradually curved in the direction of rotation reaching their sharpest angle of curvature 95 at the baffle ring —5—, the object of which is to partially counteract the centrifugal throw 100 of the fluid as the impeller is rotated.

That is, the lower portions of the blades extend some distance below the lower end of the hub —5— and are gradually curved outwardly and upwardly from said hub, the front 100 edges of the lower edges being beveled or inclined at —9— to conform to the inclination of the adjacent portions of the portion —1— of the vat —3—.

Under these peculiarly curved conditions 105 of the blades the lower front horizontal edges thereof enter the fluid with a minimum resistance as the impeller is rotated in the direction indicated by arrow —x—, Figure 1, and then gradually deflect the fluid upwardly and outwardly across the front faces thereof, the outward and upward curvature of the lower ends 110 of the blades serving to counteract the centrifugal throw of the water to a certain extent.

115 The baffle ring —7— is arranged to catch the water deflected upwardly by the lower ends of the blades and in turn again deflect the water upwardly so that the combined action of the impeller blades and baffle ring 120 serve to distribute the washing fluid upwardly and circumferentially with a considerable force over a relatively large area and through the superposed openwork trays, not shown, carrying the dishes and other utensils to be 125 washed.

Operation

When the impeller is installed in the vat in the manner described and rotated at the de- 130

sired speed the washing fluid is first picked up by the substantially horizontal lower front edges of the blades with a minimum resistance and is thereby given a slight upward deflection which is gradually increased as it follows up the incline of the blades, the upward momentum imparted to the water being gradual but accelerated as it approaches the top of the blades thereby producing a considerable upward and circumferential velocity of the water with a consumption of a minimum of power and at the same time directing the washing fluid over a relatively broad superposed area.

It is found, however, that by connecting the outer edges of the blades with a continuous baffle ring such as —7— in superposed relation to the lower ends of the blades where the centrifugal throw is greatest retards this 15 centrifugal motion of the water and deflects the same upwardly over a still wider area than that produced by the impact of the water with the front faces of the blades and by properly proportioning the diameter of the 20 baffle ring and its vertical height with reference to the lower ends of the baffle I am enabled to direct the washing fluid upwardly and circumferentially with considerable force throughout the horizontal area of the superposed portion of the vat containing the trays 25 with the dishes therein, it being understood that after the water has been impelled upwardly to the maximum it falls back by its own gravity to the conical bottom of the tub 30 when the operation is repeated to establish a continuous upward and circumferential circulation of the washing fluid.

It is evident, however, that the construction 35 and relation of the blades and baffle ring may be varied to correspond to different speeds 40 of rotation and to different degrees of inclination of the bottom of the vat and also to variations in the diameter of the vat and distance of the dish-supporting trays above the 45 impeller without departing from the spirit of this invention.

What I claim is:

1. An upright impeller for mechanical dishwashers comprising a hollow hub provided with outwardly projecting blades having their lower ends extended below the lower end of the hub and curved in the direction of rotation to a substantially horizontal plane.
2. An upright impeller for mechanical dishwashers comprising a hollow hub provided with outwardly projecting blades having their outer portions curved downwardly and forwardly from top to bottom in the direction of rotation, the radius of curvature of each blade being gradually diminished from top to bottom thereof and the lower end of each blade being extended forwardly in a plane at substantially right angles to the axis of the hub.

3. An impeller as in claim 2 in which the outer surface of the hub is flared outwardly and downwardly from top to bottom for deflecting the falling dishwashing fluid outwardly against the blades.

4. An upright impeller for mechanical dishwashers comprising a hollow hub provided with a single pair of diametrically opposite outwardly projecting blades, and a cylindrical band connecting the outer edges of the blades, said hub being tapered upwardly whereby the space between the upper ends of the hub and band is greater than that between their lower ends.

In witness whereof I have hereunto set my hand this 12th day of November, 1926.
